UNITED STATES PATENT OFFICE.

HARRY MINTZ, OF MATTAPAN, MASSACHUSETTS.

HEADREST FOR HAMMOCKS.

1,391,964.

Specification of Letters Patent. Patented Sept. 27, 1921.

Application filed October 8, 1920. Serial No. 415,541.

To all whom it may concern:

Be it known that I, HARRY MINTZ, a citizen of the United States, and resident of Mattapan, in the county of Suffolk and State of Massachusetts, have invented new and useful Improvements in Headrests for Hammocks, of which the following is a specification.

This invention relates to hammocks and more particularly to hammocks of the couch type, although in certain of its broader aspects it is equally applicable to couch devices of other forms.

It is a common practice in couch structures and more particularly in couch hammocks to provide angularly adjustable head rests, whereby the head end of the mattress or cushion may be inclined upwardly at various degrees of inclination in conformity to the wishes of the user.

Hammocks of the above type have commonly consisted in general of a substantially rectangular frame having stretched thereover a spring of wire or other suitable material upon which the mattress rests, such frame being suspended in any suitable manner from an elevated support.

As commonly arranged, the adjustable head rest comprises an auxiliary frame pivoted to the front and rear bars of the main frame and having an adjustable brace member coöperating with a ratchet-like toothed member secured to one or more of the main frame elements. In use such toothed members are objectionable, as they present sharp points or edges which frequently cause damage to the clothing of the user of the hammock, while at the same time the provision of such elements adds to the initial cost of the device.

The object of the present invention is to dispense with such toothed ratchet members, while at the same time providing for the ready adjustment of the head rest and the holding of the same in adjusted position in a secure manner. As one mode of carrying into effect the above object, advantage may be taken of the fact that the mattress supporting spring, as commonly employed in hammocks of this type, comprises a series of wires extending transversely, that is to say, in a front to rear direction across the frame and spaced apart at regular intervals longitudinally of the frame. By reason of this fact, it is simply necessary to provide the adjustable brace member for the head

rest with suitable projections adapted to engage selected ones of such transverse wires, such projections thus constituting pawls which coöperate with the ratchet device constituted by the series of transverse wires.

One mode of carrying into effect the present invention is illustrated in the accompanying drawings, in which—

Figure 1 is a fragmentary perspective view of the head end of such a couch hammock with the mattress removed to show the arrangement of the head rest and its brace.

Fig. 2 is a fragmentary side elevation of the parts shown in Fig. 1, the mattress being shown in position, and

Fig. 3 is a fragmentary plan view to enlarged scale illustrating the engagement of the brace member with the spring.

In Fig. 1 the main frame is indicated as comprising front and rear bars 1, 2, and an end bar 3. 4 indicates in general the mattress supporting spring stretched over said frame and comprising longitudinally extending wires 5 and transverse extending wires 6, such spring being resiliently secured in the frame by means of helical springs 7, all in the usual manner.

The adjustable head rest comprises side bars 8, 9 secured together by cross bars 10, the side bars being pivoted as at 11 to the front and rear main frame bars 1, 2 respectively. The adjustable brace for the head rest comprises a rod having its ends bent upward as indicated at 12, 13, the extremities of such upwardly bent portions being pivotally secured as at 14 to the side bars 8, 9 respectively of the head rest. Such

brace also comprises a central transversely extending portion 15, such portion having one or more V shaped bends therein providing the projections 16. In use the transversely extending member 15 of the brace lies substantially in contact with the longitudinal members 5 of the spring while the projections 16 pass beneath one of the transverse wires 6. As thus arranged the brace serves to support the head rest in the desired position of inclination, the projection 16 extending beneath the transverse wires 6 to an extent which precludes any probability of accidental disengagement. When it is desired to readjust the head rest, it is simply necessary to lift the same until the projections 16 have been withdrawn from be-

neath the wire 6 with which they were previously engaged when the brace may be swung to bring such projections 16 beneath any other selected one of the series of transverse wires 6, thus positioning the head rest at a new angle to the main frame.

While as herein illustrated, the brace member has been shown as comprising an angularly bent rod, it is to be understood that such brace member with its projection 16 might be formed in any other desirable manner. It is also contemplated that such cross wires 6 of the spring as serve as the ratchet elements for engagement by the pawl projection 16 may be formed of heavier wire than the remainder of such transverse elements of the spring.

While the device has herein been shown as applied to a couch hammock employing wind shields 17, 18 and having a mattress 19, it is contemplated that various of the desirable features thereof might advantageously be employed in connection with cots or couches of other than the hammock type without departing from the spirit of the present invention.

Having now disclosed the invention in a preferred embodiment of the same together with the mode of use thereof, what I claim and desire to secure by Letters Patent of the United States is:

1. A head rest for use with a couch device having a mattress supporting frame provided with longitudinally and transversely extending spring forming elements, said head rest comprising a mattress engaging frame pivotally supported adjacent one end for angular adjustment, and a brace member

pivoted to said head rest and comprising an integrally formed downwardly projecting toe constructed and arranged selectively to engage various of said transversely extending elements.

2. A head rest for use with a couch device having a material supporting frame provided with transversely extending members, said rest comprising spaced side bars pivotally supported adjacent one end for angular adjustment, and a brace member for said rest comprising a rod pivotally secured at its opposite ends to the respective side bars at points substantially removed from the pivotal supports thereof, said rod having a transversely extending portion provided with a laterally projecting integral bend, constructed and arranged to engage selected ones of said transversely extending members.

3. An adjustable head rest for use with a couch hammock having a mattress support provided with a series of transversely extending spaced wires, said head rest being pivoted for vertical angular adjustment, and a brace for said head rest comprising a rod having its ends bent substantially at right angles to its central portion and pivotally secured to the opposite sides of said head rest, and having its central portion extending transversely of said support and provided with a plurality of V-shaped bends constructed and arranged for selective engagement with wires of said series.

Signed by me at Boston, Massachusetts, this 6th day of October, 1920.

HARRY MINTZ.
